UNITED STATES PATENT OFFICE.

JAMES LEO, OF JERSEY CITY, NEW JERSEY.

DESIGN FOR A COVERED BOX.

SPECIFICATION forming part of Design No. 33,033, dated July 31, 1900.

Application filed May 7, 1900. Serial No. 15,843. Term of patent 14 years.

To all whom it may concern.

Be it known that I, JAMES LEO, a citizen of the United States, residing at Jersey City, in the county of Hudson and State of New Jersey, have invented and produced a new, useful, and original Design for a Covered Box, of which the following is a description, reference being had to the accompanying drawings, forming a part of the same.

10 In the said drawings, Figure 1 is a perspective view of the covered box, and Fig. 2 is a view of the bottom of the box.

A is the body of the box, and B is the cover thereon. The box-body has a bottom *a*, sides *b*, and ends *c*. The plane faces of the bottom, sides, and ends are at right angles to each other. Along the four lines where the bottom and sides and bottom and ends come together and also along the four upright sides 15 where the sides and ends come together are concave flutes *d*, which intersect at the lower

corners of the box—that is, at the four points where the bottom, sides, and ends come together. The cover B has the same design. It also has concave flutes *d* along the lines where the sides *b'*, ends *c'*, and top *a'* come together. 25

The leading feature of my design is the concave flutes *d* along the lines where the sides, ends, and bottom of the box come together and along the lines where the sides, ends, and 30 top of the cover come together.

I claim—

The design for a covered box substantially as herein shown and described.

In witness whereof I have hereunto signed 35 my name, this 4th day of May, 1900, in the presence of two subscribing witnesses.

JAMES LEO.
